UNITED STATES PATENT OFFICE

THEODORE C. PROUTY AND WILLIS OSWALD PROUTY, OF HERMOSA BEACH, CALIFORNIA, ASSIGNEES TO AMERICAN ENCAUSTIC TILING COMPANY, LTD., OF NEW YORK, N. Y., A CORPORATION OF NEW YORK

KILN-CAR PROPELLER

Application filed April 7, 1927. Serial No. 181,674.

This invention is a propelling mechanism which is useful, more particularly, for imparting movement to a series of product-carrying cars within a tunnel kiln for the purpose of exposing such products to the temperatures prevailing in different parts of the tunnel chamber.

In tunnel kiln practice it is required that product-carrying cars be moved at a determined speed which is usually so slow as to be barely perceptible to the eye of an observer; that such cars be propelled with a steady continuous movement in order to preclude shocks and jars which might and do have a tendency to disturb the products stacked or piled on said cars whereby irregularity in the travel is overcome and the stacked or piled products are not liable to topple over within the tunnel chamber; and, further, that a car loaded with unfired products be introduced with facility into the tunnel chamber so as to constitute one of a series of such cars adapted for movement within said tunnel chamber, such introduction of an additional car at one end of the series of such cars and the movement of the additional car into the entry end of the tunnel chamber taking place concurrently with the delivery from the opposite end of the tunnel chamber of a car loaded with matured and cooled products, whereby the kiln is adapted for service continuously or without interruption in the transportation of the products or in the maintenance of the appropriate temperatures at the pre-heating, maturing, and cooling zones of such tunnel chamber.

In a co-pending application namely, Serial No. 177,914, filed March 24, 1927, we have disclosed one form of tunnel kiln adapted for the heat treatment of the bisque composition of ceramic products, such as floor and wall tiles, said kiln embodying a continuous tunnel chamber open at both the entry end and the delivery end, together with a track extending for the length of said tunnel chamber, with the opposite ends of said track projecting beyond said entry end and said delivery end of the tunnel chamber. As therein disclosed, the track is inclined perceptibly, such inclination being from the

delivery end toward the entry end of the tunnel chamber, the effect of which is to attain a gravity movement of the cars toward the entry end of the tunnel chamber whereby the cars are in abutting contact throughout the series within said tunnel chamber. This tendency of the abutting cars for movement by gravity toward the entry to the tunnel chamber is counteracted by the operation of the propelling mechanism, the latter being in service continuously and being operable for imparting a steady slow movement to all the cars within the tunnel chamber.

The object of this invention is to simplify the construction of a car-propelling mechanism adapted for the performance of the functions of moving at slow speed a series of loaded cars within a tunnel kiln, and for the introduction from time to time of additional cars into the series and without arresting the movement of said cars constituting the series.

In the present invention, we employ an electric motor as the prime mover for the operation of the series of cars, and with said motor there are associated a speed reduction mechanism, and an endless car-driving member operable from said motor through the action of said reduction mechanism. The car-driving member is, preferably, in the form of an endless chain positioned substantially at the open entry to the tunnel chamber, said endless chain extending partly within the tunnel entry and extending, also, part way out of and beyond the tunnel entry. This endless chain is equipped with a plurality of car-engaging elements usually in the form of flat bars, said elements being spaced with respect to each other and each element being engageable with a trigger provided on the underframing of a car whereby the motion of the chain is communicated to a car to be propelled into the tunnel, and thus the cars in series are moved within and through the tunnel chamber.

Other functions and advantages of the invention will appear from the following detailed description taken in connection with the accompanying drawings, wherein

Figure 1 is a sectional elevation of a tun-

nel kiln equipped with a car propelling mechanism of this invention.

Figure 2 is a horizontal section through the entry end of the tunnel chamber on the line 5 2—2 of Figure 1, illustrating the car-propelling mechanism in plan view.

Figure 3 is a vertical section on the line 3—3 of Figure 2.

Figures 4 and 5 are views in side elevation 10 and end elevation, respectively, illustrating the relation of the speed reduction units to the electric motor drive.

A designates a tunnel kiln of suitable construction, such as the bisque kiln disclosed in 15 our co-pending application Serial No. 177,914, filed March 24, 1927. Said kiln includes a tunnel chamber B, the entry "b" of which is normally open to the outside atmosphere. Within the tunnel chamber B extends a 20 track the rails C of which are preferably inclined somewhat, so that the track end at the entry "b" is not as high as the end of said track at the delivery end of the tunnel chamber, the inclination of said rails C being 25 downwardly toward the entry "b", whereby the series of kiln cars D tend to move by gravity into abutting contact one with the other, and thus the series of cars within the tunnel chamber are engaged automatically to 30 retain such cars in the required close relation throughout the series extending the full length of said tunnel chamber. The rails C of the track are extended for a desired distance beyond the open entry "b" to the tunnel 35 chamber, and with said extended part of the track cooperates a transfer car, not shown herein for the reason that it is ordinary in the tunnel kiln art.

Each kiln car D may be, and preferably is, 40 constructed as disclosed in our co-pending application with a rigid substantial underframing "d", composed of metal bars or beams welded or otherwise rigidly fastened together. Said underframe is equipped with hangers 45 for the wheels "d¹" adapted to travel on the rails C, and in addition to the described construction, the car D is provided with a trigger E, herein shown as a single piece of metal rigidly fastened, as by welding, to a 50 part of the underframing "d", said trigger E occupying an inclined depending relation to the car and its underframing whereby the trigger is engageable with the driving chain, presently described.

55 The kiln structure is built or erected upon a metal underframing composed of longitudinal beams "a" and transverse beams "a¹" suitably united, as by welding said beams, whereby the kiln structure occupies a raised 60 position above the level of the floor, and thus there is a free space beneath the kiln for the radiation of heat and for the flow of atmospheric air beneath the kiln for substantially the length and width of said kiln structure.

Beneath the entry portion "b" of the tunnel kiln we provide a metallic frame F for supporting the various elements of the kiln drive, said metallic frame comprising appropriate beams and bars united rigidly together, as by welding. It is preferred to use a metal frame exposed for access partly at the side of the kiln structure and partly beyond the entry "b" to the tunnel chamber, other parts of said frame F being below the kiln 75 structure and the tunnel chamber thereof.

The power required for the propulsion of the cars within the tunnel chamber, at the speed selected, is furnished by any suitable 80 motor or engine or other source of power, but in the drawings we have shown an electric motor G, mounted on the frame F or a part thereof, said motor being outside of the kiln structure and at one side thereof, although the location of the motor is not a factor in our invention.

The speed of the motor shaft is reduced through the agency of any preferred speed reduction mechanism, but in the example shown, we employ a plurality of reduction units H, H¹, of a standard 85 type, both units being outside of the kiln structure and supported on the frame F. The motor shaft "g" is shown as having a pulley "g¹", engaged by a belt "g²" which drives a pulley "h" of the first reduction unit H and the shaft "h²" for imparting motion to the second reduction unit H¹. This second unit drives a shaft I composed of alined sections, coupled by a clutch "i", the latter being shiftable by the movement of a shipper lever "i¹". The counter shaft I is journaled in appropriate bearings on frame F outside of the kiln, and this shaft is provided with a sprocket wheel "j", engaged by an endless 90 sprocket chain J, extending alongside of the kiln, exteriorly thereto. Said chain engages with a sprocket wheel "j¹" provided on a horizontal shaft K, journaled in bearings on the frame F, and extending beneath the kiln structure, at a suitable distance inwardly 95 from the entry end "b" to the kiln chamber. Said shaft K is provided with a sprocket wheel "k", and parallel to the shaft K is another shaft L, the latter being journaled in 100 bearings provided on the frame F, and being positioned outside the kiln structure and beyond the entry "b" to the tunnel chamber. Said shaft L is provided with a sprocket wheel "l", disposed in alinement with sprocket wheel "k" on shaft K, and with said alined 105 sprockets "k", "l", of the two shafts K, L, is engaged the propelling chain M adapted for 110 the propulsion of cars within said tunnel chamber.

The propelling chain M, or equivalent endless member, is positioned between the rails of track C, and it extends part way outside of the kiln structure, beyond the entry "b" to the tunnel chamber, and it extends, also, beneath the kiln structure, for an appropriate 115 120 125 130

distance inwardly with respect to the entry "b" of the tunnel chamber. Said propelling chain is driven at slow speed by the train of devices between the shaft K and the motor, and this chain is provided with means for engagement with or by the triggers on the kiln cars. As one means for effecting such car engagement at the required periods in the movement of the propelling chain, we have 5 shown a plurality of coupling bars "m", "m", fixedly attached to said chain and spaced relatively to each other. The car-engaging members "m", travel in a path adjacent to or intersecting with the path of the car trigger 10 when said car is in position for introduction into the tunnel chamber, and the engagement of one coupling member "m" of the propelling chain M with a car, is maintained for that period of time required to effect the introduction 15 of said car into the tunnel chamber; in fact one coupling member of the chain remains in engagement with a coupling member of one car until the next succeeding car shall have been positioned for the engagement with 20 its coupling member by the next coupling member "m" of said propelling chain. The cars are adapted to be placed at the entry end to the tunnel chamber for engagement successively by the coupling bars "m" of the 25 propelling chain, and as each car is thus pushed into and through the entry "b", the movement of said car brings it into abutting engagement with the car next preceding it, whereby the force applied to the last car of 30 the series acts to propell all the cars within the tunnel chamber, such propulsion of the series of cars being at the slow speed given to the propelling chain by the motor acting through the reduction units H, H¹, and the 35 series of shafts herein described.

The upper run or lead of the endless propelling chain has a tendency to sag and this may move the chain bar "m" free from the trigger of the car, thereby uncoupling the 40 chain from the car. To overcome this uncoupling, a supporting element in the form of a plate "n" is fixedly attached to parts of frame F, said supporting element "n" being below the upper run or lead of the chain and 45 in engagement therewith. The upper run of the chain is free to slide upon the plate "n" which acts as a support to retain the traveling chain in the required relation to the trigger of the car, thus overcoming a tendency of 50 the chain to be uncoupled by sagging of the chain away from the car. A similar plate "n¹" is provided on the frame for contact with the sagging under run or lead of the endless chain M.

When the kiln is in service, the tunnel chamber contains a series of cars which are in 55 abutting contact one with the other, the last car of the series being engaged by one member "m" of the propelling chain, so that all 60 the cars are pushed through the tunnel cham-

ber. Before the member "m" of the propelling chain is moved far enough into the chamber to be carried around the sprocket wheel "k" of shaft K and to be disengaged from said car last introduced, another car is 70 shifted by the transfer table to a position in line with the track C and with the series of cars. At the proper time in the travel of the chain M, the other member "m" is moved into engagement with the trigger of the car thus 75 aligned with the track, such engagement taking place prior to the disengagement of the chain from said car just beyond the kiln entry "b", and thereupon the chain operates to impart movement to the freshly introduced car, 80 and the operations are repeated for keeping the tunnel chamber filled with loaded cars.

Our propelling mechanism comprises relatively few parts, each simple in construction and installed so as to be accessible readily for 85 inspection, repairs and replacement, if required. The reduction units H, H¹, which we employ and the motor are standard constructions well known in the arts so as to be replaced should they get out of order. The 90 endless chain affords means for engagement successively with the added cars as and when placed in series, and said chain is a simple and inexpensive part easily inspected and repaired. The propelling mechanism as a 95 whole is readily assembled and installed, and if desired some of the parts outside of the kiln may be encased to exclude dust and dirt and to preclude injury to the workmen.

It will be noted that the propelling mechanism embodies a simple but effective organization and construction of parts including a single element, such as a trigger, on each car, and a single driving chain provided with a plurality of car-engaging members, each in 100 the form of a simple bar. The propelling chain however occupies a novel relation to the tunnel chamber, at the entry end "b" thereof, said propelling member ranging 105 lengthwise of the tunnel entry, with one end of the chain beyond the tunnel kiln and with the other end positioned inwardly with respect to the entry "b" of said tunnel chamber, the effect of which is that the chain moves each added car for a distance required to 110 introduce said added car into the tunnel chamber. The added car abuts against the next preceding car of the series, and the movement given to the added car by the action of the propelling chain affords the pushing 115 effort required to propel all of the cars of the series within the tunnel chamber. As previously stated, the cars move slowly through and within the kiln for exposing the ceramic products for the periods of time required to 120 the temperatures prevailing within the several zones, i. e., the pre-heating, maturing (firing), and cooling zones, and as indicating the slowness of the car movement, we mention that in the bisque kiln disclosed in our 125 130

co-pending application, the cars are moved at a speed of .368 inch per minute of time, although it is to be understood that we do not intend to restrict the car speed to the limit stated, for the reason that such speed may be increased or decreased as and when required.

The cars are propelled within the tunnel chamber at the speed of the drive chain, one member "m" of which is, in effect, coupled to the end car of the series by the engagement of the car trigger with the chain member "m". Said chain moves relatively to the kiln entry "b" for a distance exceeding the length of the car. The members "m" of the drive chain are spaced relatively to the cars so that in the travel of the chain one member "m" engages with a car to be added to the series prior to the disengagement of the other chain members from the car next preceding the car to be added, and thus the series of cars are moved continuously and there is no cessation in such car movement by the addition of cars to the series.

Having now described our invention, what we claim as new and desire to secure by Letters Patent is:

1. In a car propeller, the combination with a chamber adapted for containing a continuous series of cars in abutting relation, of a propelling member acting with a continuous movement in one direction for applying propulsive energy to an end car of the series and to effect the movement of the abutting cars throughout the series whereby all the cars are advanced within the chamber, and means for imparting movement at slow speed to said propelling member.

2. In a car propeller, the combination with a chamber having a track whereon travels a continuous series of cars positioned in abutting contact one with the other and adapted for continuous movement in one direction for exposing the loads to treatment within said chamber, of a propelling member adjacent the entry to said chamber, said propelling member acting with a single continuous movement and co-operable with an end car of a series for effecting the application of propulsive energy in one direction to all the cars of the series, and means for imparting slow movement continuously to said propelling member, whereby successive cars are introduced in series with the cars in said chamber and all the cars are propelled by power applied to an end car of said series.

3. In a car propeller, the combination with a chamber having means for the reception of a series of cars positioned in abutting contact and adapted for movement concurrently with one another within said chamber, of an endless propelling member positioned adjacent an entry to said chamber, said propelling member being co-operable with an end car of the series and operating to apply a propulsive force in one direction to said end car whereby

all the cars of the series are moved continuously within the chamber, and driving means for imparting movement continuously and at slow speed to said propelling member.

4. In a car propeller, a chamber having a track for the reception of a series of cars positioned in abutting contact and adapted for concurrent movement in said chamber, a single endless propelling member at the entry to said chamber, a plurality of car-engageable devices carried by said propelling member and spaced for co-operation with a plurality of cars adapted to be introduced successively into the chamber and in the desired abutting contact with an end car of the series, and means for driving the propelling member continuously and at slow speed whereby all the cars of the series are adapted for movement by the propulsive energy of the single propelling member.

5. In a car propeller, a chamber having a track for the reception of a series of cars positioned in abutting contact, a single endless propelling member positioned at the entry to said chamber and extending lengthwise thereof for one part of the propelling member to operate within the chamber and for another part thereof to operate exteriorly with respect to the chamber entry, a plurality of car-engaging devices movable with the propelling member and spaced relatively one to the other for co-operation with cars adapted to be introduced successively into the chamber, and means for driving the propelling member continuously in one direction and at relatively slow speed.

6. In a car propeller, in combination, a chamber having a track for the reception of a series of cars positioned in abutting contact, a single endless propelling member ranging lengthwise of the entry to said chamber, a plurality of car-engaging means carried by the propelling member and spaced thereon for co-operation with cars adapted to be introduced successively into said chamber, a motor, speed reduction gearing intermediate the motor and the endless propelling member, and controlling means for said speed reduction gearing.

7. In a car propeller, the combination with a chamber adapted for containing a continuous series of cars in abutting relation, of an endless chain acting with a continuous movement in one direction for applying propulsive energy to an end car of the series and to effect the movement of the abutting cars throughout the series, whereby all the cars are advanced within the chamber, and means for imparting movement at slow speed to said endless chain.

8. In a car propeller, a chamber having a track for the reception of a series of cars positioned in abutting contact and adapted for concurrent movement in said chamber, a single endless chain at the entry to said chamber,

a plurality of car engageable devices carried by said endless chain, and spaced for co-operation with a plurality of cars to be introduced successively into the chamber and in 5 the desired abutting contact with an end car of the series, and means for driving the endless chain continuously and at slow speed whereby all the cars of the series are adapted for movement by the propulsive energy of

10 the endless chain.

9. In a car propeller, a chamber having a track for the reception of a series of cars positioned in abutting contact and adapted for concurrent movement in said chamber, a single endless chain at the entry to said chamber, a plurality of devices mounted on said chain, each device being adapted to contact a projection on a car to progress the car for a distance in the chamber and means for driving the 15 said chain continuously and at slow speed whereby all the cars of the series are adapted for movement by the propulsive energy of the said chain.

10. In a car propeller, a chamber having inclined tracks for the reception of a series of cars positioned in abutting contact, a single endless propelling member positioned at the entry to said chamber and extending into said chamber for only a portion thereof, a plurality of car engaging devices movable with the propelling member and spaced relatively one to the other for co-operation with cars adapted to be introduced successively into the 20 chamber, and means for driving the propelling member continuously in one direction and at relatively slow speed, whereby all the said cars are moved while being maintained in abutting relation.

In testimony whereof we have signed our 25 names hereto at Hermosa Beach this 23d day 40 of February, 1927.
